tion of Delaware

Application June 13, 1939, Serial No. 278,949

13 Claims. (Cl. 62—5)

This invention relates to refrigeration systems, and particularly to systems of the absorption type utilizing a volatile refrigerant, such as ammonia, and a volatile solvent, such as water.

Systems of this type have been in use for many years and were used for furnishing refrigeration where a heat source such as exhaust steam was available. Although systems of the prior art are quite flexible in operation, every change in refrigerating load required certain adjustments to be made manually and with considerable accuracy, in order to obtain efficient operation. It is the purpose of this invention to avoid this characteristic, provide a system which is automatically responsive to changes in load without material loss of efficiency, and at the same time simplify the apparatus required. Broadly stated, the apparatus comprises the usual elements such as generator, condenser, receiver, evaporator, absorber, heat exchangers, and strong aqua pump, but includes a bubble tower in place of the usual analyzer, dehydrator or equivalent device.

Whereas in most prior art systems it is necessary to make use of a so-called analyzer for reducing the heat load on the generator and for reducing the temperature and water content of the vapor, and a dehydrator for separating the water vapor from the ammonia as it is given off from the generator, the present invention contemplates the use of a single element in the form of a bubble tower for performing these and added functions. By the use of this bubble tower, the apparatus is simplified, its flexibility increased, steam consumption reduced, and automatic control in response to widely and rapidly varying load conditions made possible.

In the apparatus of the prior art it has been practically impossible to prevent the transfer of substantial quantities of water to the evaporator, which water necessitated the developing of lower suction pressure in the system to accomplish the same refrigeration, and required frequent purging to remove such water. The new system substantially avoids delivery of water to the evaporator and, consequently, does away with the need for frequent purging of water from the evaporator. Furthermore, it becomes possible to control the system automatically and to avoid the necessity of constant attention of an operator to perform manual adjustments in maintaining the liquid in the various elements at proper levels.

The improved result, brought about by the practice of the present invention, is secured by replacing the analyzer and dehydrator with a

bubble tower, by the addition of a dual strong aqua return from the absorber, one branch of which delivers to the generator while the other branch delivers a limited quantity of strong aqua to an intermediate point in the bubble tower; by the return of a limited quantity of liquid anhydrous ammonia to the top of the bubble tower from the condenser, and by other refinements which will be pointed out.

- 10 As a result of this arrangement, the gas leaving the generator is cooled so as to approximate the condensing temperature, and the ammonia gas is so effectively dehydrated that the ammonia entering the condenser is freed of water to a much greater degree than has been possible with apparatus of the prior art. In the functioning of this improved mechanism the liquid anhydrous ammonia condenses the water vapor out of the ammonia gas and in so doing is completely re-evaporated and re-enters the condenser from the top of the bubble tower. The strong aqua fed to the bubble tower performs the function of desuperheating the vapors passing upwardly through the tower from the generator.
- 15 20 25 The strong aqua fed to the heater elements assists the flow of aqua in the generator by exerting an ejector pump action.

The main effect of the present invention is, therefore, to simplify the operation of the system, causing it to adjust itself automatically to changing load conditions in such manner that it is inherently stable, and otherwise to improve the efficiency of, and reduce the number of parts required in absorption systems.

30 Whereas in prior art apparatus a substantial change in load on the system necessitated a manual readjustment of generator aqua load, and aqua level in the strong aqua tank to meet changing conditions, the present system compensates automatically by maintaining the proper ratio between the aqua and vapor, thus permitting a mere change in steam flow to meet the new load conditions without unbalancing the system.

35 The invention will be explained in connection with the accompanying drawings, in which:

Figure 1 is a flow sheet indicating the layout of one embodiment of the present invention;

Figure 2 is an enlarged diagrammatic detail of the bubble tower, generator, condenser and receiver shown in Figure 1; and

Figure 3 is a sectional view showing the details of the bubble plates employed in the bubble tower illustrated.

Figure 1 of the drawings shows a typical lay-

out embodying the present invention as applied to an absorption system of the ammonia-water type. As illustrated, it includes conventional components such as a generator G, condenser C, receiver R, evaporator E, absorber A, heat exchanger H, and strong aqua pump P, and, in addition, the novel bubble tower T interposed between the generator and condenser.

In order to facilitate understanding of the present invention, the separate elements of the combination will be described individually, and then the operation of the system as a whole set forth.

The generator, designated as a whole by the reference character G, comprises (see Fig. 2) a surge drum 5 adapted to contain a strong solution of ammonia gas in water, this drum being connected to the strong aqua return 6, vapor outlet 7 and weak aqua outlet 8. Connected to the surge drum 5 in parallel relation with one another are a plurality of heater units or calandrias, preferably of the shell and tube type, adapted to be supplied with a heating medium, such as steam, from a header 9. Each of these calandrias comprises a shell or casing 11 having a top header connected by a horizontal tube 12 to the drum 5, and a bottom header connected through a pipe 13 to a vertical pipe 14 leading into the bottom of the surge drum. The arrangement is such (see Fig. 1) that the ammonia-water solution in the drum may circulate from the drum 5 downwardly through pipe 14, horizontally through pipe and header 13, up through the tubes 15 and back to the surge drum through the pipe 12. Steam supplied through the header 9 passes into the casing 11 in contact with the outer surface of the tubes 15 and flows out to a common condensate return header 16. The heat delivered by this steam and controllable by valves 17 induces a thermal circulation through each calandria, and the vapor produces a gas lift to increase the circulation.

The liquid level in drum 5 is above the upper tube sheets of the calandrias, and cross baffles 18 (see Fig. 2) partially segregate different portions of the drums associated with the various calandrias.

In order to prevent gas locks in the calandrias, caused by failure of the tubes to prime, there is provided a common strong aqua header 19 fed by the return from the strong aqua pump and this header has a plurality of connections 19, one leading to each of the pipes 13 under the control of a manually operable valve 21. These valves 21 control the flow of strong aqua under pressure to nozzles 20 which direct jets into the throats 22 and thus stimulate circulation through the corresponding calandria. It will be understood that although only three calandrias are shown in Fig. 2, it is possible, according to the present invention, to use any desired number of these units in parallel, and the operation is such that the concentration of the solution in the surge drum 5 decreases progressively from the strong aqua return end connected to pipe 6 where it is a maximum to the opposite end of the drum where the weak aqua is discharged for return to the absorber. Increasing amounts of aqua are fed to the heaters through valves 21 from the strong end to the weak end of the drum, so that the circulating rates are approximately uniform and uniform high heat transfer rates are secured.

The end of the surge drum 5 adjacent the weak aqua discharge 8 embodies a liquid level

responsive float 25 disposed in a chamber 26 having a connection 27 to the top of the surge drum and a similar connection 28 to the bottom of the same. The float 25 controls the supply of air under pressure from pipe 29 to the pneumatic motor which controls valve 24, and thus regulates the amount of strong aqua which is returned to the generator. An initial approximate adjustment is made by means of the manually controlled valves 20 and 29.

It will be understood that the flow of steam to each of the calandrias may be controlled individually by means of the control valves 17. The drip valves 23 are normally wide open, line 16 being connected to a suitable steam trap: (not shown). Similarly, the injectors 22 may be controlled by manipulation of the valves 21 in order to proportion the circulation in the various heaters or calandrias to control the heat transfer rates as above suggested.

In accordance with the principles underlying the present invention, the vapor outlet 7 from the surge drum 5 of the generator leads to a space 42 in the bottom of a bubble tower T embodying a plurality of bubble plates adapted to carry a shallow body of liquid through which upwardly passing vapor must pass before it is discharged to the condenser. Although various types of bubble tower might be utilized for this purpose, the tower illustrated is in principle satisfactory. This tower T comprises an upright casing or shell 24, closed at the top and bottom by heads 25 and 26, respectively. The bottom head 26 contains a strong aqua discharge connection 6 leading to the surge drum 5, while the top head 25 contains an ammonia vapor discharge pipe 27 leading directly to the top of the condenser C, as shown in Fig. 1. The bottom of the tower T must be at such height that gravity flow to the surge drum 5 will occur. (See Fig. 2.)

The internal structure of the bubble tower will be best understood by reference to Figs. 2 and 3, where reference character 28 designates a plate sealed to the walls of the shell 24 and having a liquid discharge pipe 29 for permitting the flow of liquid to the next lower level, the pipe being trapped at its lower end in a cup 30 in which it dips below the liquid bath. The plate 28 is perforated as at 31 and this perforation is surrounded by a tubular upstanding rim or flange 32 which cooperates with the depending flange 33 of an inverted cup or bell 34 associated with each of the openings 31. The bell 34 is secured to the rim 32 by means of a strap 35 and a bolt 36. The depending flange 33 is serrated in such a way that gas escape openings are provided below the minimum level of liquid on the plate 28 maintained by upstanding flange 37 of the cup at the top of the pipe 29.

The result of this arrangement is that when liquid flows onto the plate 28 from a cup 30, it accumulates to a level defined by the flange 37, and when above that level, some liquid is caused to discharge through the pipe 29 to the bubble plate next below. So long as liquid is present to the depth defined by the flange 37, gas entering the openings 31 from below in escaping upwardly through the tower must pass through the layer of liquid which is present between the rim 32 and the depending serrated flange 33. The effect of this arrangement is to provide as in the usual manner a tortuous passageway through which gas escapes upwardly through a layer of liquid or a liquid film in passing each of the bubble plates. A constant flood of liquid

on the two lower plates in the bubble tower is assured from a strong aqua return connection 39, while the four upper plates illustrated are always flooded with substantially anhydrous liquid ammonia from the pipe 41 discharging from the bottom of condenser C.

The adjustment is such that no anhydrous liquid ammonia entering the pipe 41 can escape at the bottom of the tower, all of it being re-evaporated to gaseous form before it reaches the discharge space 42 in the bottom of the tower. The supply of anhydrous liquid ammonia is, however, adequate to insure a minimum depth of liquid on the four topmost bubble plates or those which are disposed in the casing 24 above the strong aqua inlet 39. The two bottom bubble plates are similarly filled with liquid from the strong aqua connection 39 so that there is no possibility of any of the plates becoming dry, or of any ammonia and water vapor escaping upwardly through the tower from chamber 42, without traversing the liquid films provided by the bubble plates illustrated.

To simplify the drawings the bubble tower is shown with two plates below and four above the strong aqua inlet, and these are more than are theoretically necessary. However, the tower is never 100% efficient and in practice three have been used below the strong aqua inlet and six above, with excellent results.

The bubble tower incorporated according to the teachings of the present invention, assures the escape of substantially water-free ammonia gas through the discharge connection 27 leading to the condenser. The presence of anhydrous liquid ammonia on several of the bubble plates assists materially not only in dehydrating the ammonia gas coming from the generator, but in reducing the temperature of that gas to substantially condensing temperature when it leaves the bubble tower. In other words, the function of the anhydrous liquid ammonia connection is to reduce the temperature of the escaping ammonia gas, and at the same time assist in a thorough dehydration of the ammonia vapor discharged from the generator. The intermediate strong aqua return connection 39, serves to de-superheat the ammonia vapor passing upwardly through the tower and thus assists in the deposition of entrained water vapor. The net effect of the connections 39 and 41 is to ensure the escape to the condenser of water-free or substantially water-free ammonia gas approximately at condensing temperature and free from superheat. The liquid ammonia delivered by the condenser is as nearly anhydrous as commercial liquid ammonia sold for refrigerating purposes.

The condenser C serves to liquefy the gas from tower T in the usual manner. While it is preferred that the condenser be of the shell and tube water cooled type, this is not essential. However, as shown the condenser comprises a shell 43 carrying water boxes 44 and 45 between which water tubes extend. The water box 44 has inlet and outlet water connections 46 and 47, for cooling water, whereas the shell has ammonia vapor supplied to it around the water tubes through the pipe 27. It discharges a limited quantity of liquid ammonia through the pipe 41 leading to the top of tower T, but the main discharge is through the pipe 48 leading to receiver R. The receiver R contains a sight glass 49. A discharge pipe 51 leads to the evap-

orator E by way of expansion valve 50. The line 52 leads to the absorber A.

Whereas it is usual to employ an absorber made up of a single drum, it is preferred, according to the present invention, to embody this element in the form of several connected shells in which the aqua is sprayed over water cooled tubes. These shells are arranged in series to produce aqua increasing in concentration as it flows through the series. As shown, the absorber shells are in vertically superposed relation and are supplied in parallel with ammonia gas from pipe 52, through pipes 56, 57 and 58. The weak aqua return pipe 59 leading from the exchanger H delivers weak aqua through parallel pipes 61 and 62 to spray pipes 60 in the top of the first shell 53 of the absorber, thus the tubes in the absorber are wetted with weak aqua. From the bottom of shell 53 it flows to spray pipes in the second shell 54, and similarly from shell 54 to spray pipes in the shell 55, from which a strong aqua discharge connection 63 leads to the strong aqua tank 64.

Tank 64 has a sight gage 65 and a discharge line 66 leading to the strong aqua pump P. Consequently, ammonia gas is supplied to each of the shells of the absorber, and there meets and is absorbed by the sprayed aqua. The concentration increases progressively from top to bottom of the series of shells and reaches its maximum at the bottom of shell 55 where it discharges into the strong aqua tank 64. The absorber shells are cooled by liquid supplied through inlet 48 which, after passing through water tubes in the shells, is discharged at 40.

The strong aqua pump P, preferably of the centrifugal type or driven by a rotary device such as a turbine, serves to supply the strong aqua to the heat exchanger H, here shown as comprising two shell and tube units 67 and 68, although a single unit may be substituted.

As is usual, the purpose of this exchanger is to increase the temperature of the strong aqua returning to the generator, and to reduce the temperature of the weak aqua returning to the absorber by heat exchange between the two.

The weak aqua coming to the absorber from the generator surge drum passes through pipe 8 and through the tubes of the shell and tube units 67 and 68, respectively, then through pipe 59 to the absorber. The strong aqua flows from tank 64 through pipe 66, pump P, pipe 71, through shells 68 and 67 to pipe 72.

As indicated above, prior art systems have required manual adjustment of the strong aqua level in the system in accordance with changes of load and in accordance with changes in the supply of heat necessitated by changes of load. The present invention does away with such manual adjustments by providing automatic control of the system in order to produce and maintain a predetermined ratio between the weak aqua and the vapor flowing to the absorber, and a definite differential between the temperature of refrigerant leaving the condenser and the temperature of vapor leaving the bubble tower.

Although numerous types of control may be used to carry out these functions, the diagrammatic illustration given herein includes pneumatically actuated control instruments which respond to the quantities above stated.

The rate at which liquid anhydrous ammonia is supplied to the tower through connection 41 should be controlled to maintain a chosen differential between the temperature of liquid leav-

ing the condenser and the temperature of ammonia vapor leaving the tower. In practice, it has been found that a temperature difference between these points of approximately 5° F. induces highly satisfactory operation. Accordingly there is disposed in the top of the tower, at 75, a thermal bulb leading through a tube 76 to a differential controlling instrument 77. A similar bulb 78 is associated with the liquid line 48 leading from the condenser C to the receiver R, and is connected through a tube 79 with the instrument 77. An air supply line 81 leads to the instrument 77, while a pneumatically actuated valve 82 interposed in liquid line 41 is controlled by instrument 77 through branch line 83. The instrument 77 which may be of any suitable known form operates to vary the air pressure in the branch line to maintain the desired 5° temperature difference between the points 75 and 78. Instruments of this type are well-known in the control art.

The other automatically controlled factor is the relation of flow rates between the gas discharged from evaporator E to the absorber and the weak aqua delivered by pipe 59 to the top unit 53 of the absorber A. To effect this control, a pneumatic instrument 84 connected to the air supply line 81 is provided and controls a pneumatically actuated valve 86 in line 59. The line 59 contains a measuring orifice 87 connected by two pressure transmitting lines 88 and 89 to the instrument 84. Similarly, the line 52 leading from evaporator E to the absorber contains a measuring orifice 91 having separate pressure transmitting lines 92 and 93 leading to the instrument 84. The instrument 84 is of conventional construction and response to the pressure drops across the orifices to maintain an adjustment of valve 86 such that the flow of weak aqua to the absorber is coordinated with the flow of ammonia vapor from the evaporator. The mechanics of the control instrument are well known and are not a feature of this invention. The coordination of control rates is, however, novel and a feature of the invention.

The operation of the system as a whole is as follows: The instruments 77 and 84 are adjusted in accordance with the temperature differential and relative flow rates which are to be maintained thereby, as above set forth. Then, as steam is supplied through the header 9, strong aqua circulation is induced in the generator surge drum and through the separate heaters or calandrias associated with it. A mixture of ammonia vapor and water vapor is discharged through connection 1 to the space 42 in the bottom of the tower T and this vapor passes upwardly through the tower where it is deprived, step by step, of its water vapor and superheat. At the same time its temperature is lowered. The ammonia condenses as a liquid in the condenser, a controlled portion of it being discharged through the line 41 to the top plate of tower T, and thence downwardly through the tower until it is all re-evaporated and passes upwardly and out through the discharge connection 27 as gaseous anhydrous ammonia.

The major portion of the condensed liquid ammonia is discharged through pipe 48 to the receiver whence it flows through the expansion valve to the evaporator E. There it takes up heat in the usual manner and is discharged as ammonia gas through the connection 52 to the absorber A.

The weak aqua formed in the discharge end 75

of surge drum 5 of the generator escapes through the pipe 8, passes through the exchanger and thence through pipe 59 to the top unit 53 of absorber A, and then downwardly through the absorber, absorbing the gaseous ammonia coming from the evaporator, so that aqua of maximum strength employed flows to the strong aqua tank 64 and thence returns to the generator through either of two circuits. One of these embodies the strong aqua return to the intermediate point in the tower through pipe 39 and thence through strong aqua return 6 to surge drum 5. The other circuit is from pipe 72 through pipe 74 to the strong aqua header 18, or from pipe 13 directly to the surge drum by way of strong aqua return line 6.

The amount of liquid anhydrous ammonia returned to the top of the tower is controlled automatically by the instrument 77, as described. Similarly, the return of weak aqua to the top of the absorber is controlled by the valve 86 in response to the flow conditions affecting instrument 84. The rate of circulation of strong aqua is under the control of valve 94 which is regulated according to the level of the aqua in the discharge end of surge drum 5.

When the level of liquid at the discharge end of the surge drum rises, the valve 94 tends to reduce the flow through pipes 72, 39, and consequently also the flow through pipe 13 to the generator and pipe 74 to the strong aqua header. The location of the valve 94 at a point beyond the heat exchangers prevents foaming of the liquid in the heat exchangers. The location of the valve 86 beyond the heat exchangers also prevents foaming. Elimination of foaming permits the use of small valves and ensures complete flooding of the exchangers.

The adjustment of valve 94 preferably is such as to pass just sufficient strong aqua to absorb the heat capacity of the vapor entering tower T through line 1. This permits the use of a tower T of minimum size, decreases the weir length required in the tower and provides excess liquid for ejector operation at the heaters.

The principles herein described bring about important results in simplicity of structure and efficiency of operation. The range of capacities is increased enormously so that for the first time it becomes practicable to operate an absorption system of the ammonia-water type with automatic control giving substantially uniform efficiency, and increased flexibility in response to changing loads. The ammonia gas leaving the tower is so nearly anhydrous that purging of the system to remove water from the evaporator is practically never required.

What is claimed is:

1. In a refrigeration system of the absorption type, comprising a generator, a condenser, an absorber, an evaporator, and means for conveying refrigerant from the generator to the evaporator; a bubble tower interposed between the generator and condenser and having a plurality of bubble plates, said tower serving both to rectify and to cool the ammonia vapor passing therethrough; means for supplying substantially anhydrous ammonia liquid from said condenser to said bubble tower adjacent the top thereof to flood certain of the plates with liquid ammonia; means for returning strong aqua from said absorber to said generator; and supplemental strong aqua supplying means connecting the absorber and an intermediate point in said tower

to flood the remainder of said plates with strong aqua.

2. In an absorption system of refrigeration employing a volatile refrigerant and a volatile solvent therefor and comprising a generator, an absorber, a condenser, and an evaporator, said absorber comprising a plurality of parallel spray-type units receiving weak aqua in series from said system and ammonia gas in parallel from said evaporator; means for supplying substantially pure refrigerant to said evaporator, said means comprising a bubble tower interposed between said generator and said condenser, a split return for strong refrigerant solution from said absorber to an intermediate point in said bubble tower and to said generator, and a substantially anhydrous liquid refrigerant return from said condenser to the top of said bubble tower.

3. In an absorption system of refrigeration employing ammonia and water, a generator; an absorber; a condenser; an evaporator; and means for supplying substantially pure ammonia to said evaporator, said means comprising a bubble tower interposed between said generator and said condenser to both rectify and cool the vapors passing upwardly therein, a strong aqua return from said absorber to an intermediate point in said tower and from said absorber to said generator, and a liquid ammonia return from said condenser to said tower at a point above said strong aqua return.

4. In an absorption refrigeration system of the ammonia-water type, a source of strong aqua under pressure; a generator comprising a plurality of aqua heating units connected in parallel relation to one another and emptying into a common surge drum; means connected to said strong aqua source for causing circulation of the aqua in said heating units; a bubble tower connected to the gas outlet of said generator surge drum to rectify and cool the vapors passing upwardly therein; an evaporator; an absorber; a condenser connected between said tower and said evaporator and having a liquid ammonia discharge to the top of said tower; means for delivering gas from said evaporator to said absorber; and means for supplying strong aqua from said absorber to said generator in two branches one of which leads to said tower between said liquid discharge from the condenser and the bottom of the tower, and the other of which leads directly to said surge drum.

5. In an absorption refrigeration system of the ammonia-water type, comprising a condenser, an evaporator, an absorber, a generator and means for pumping strong aqua from the absorber to the generator, said generator comprising a surge drum fed by the strong aqua pumping means and having a plurality of parallel related units adapted to heat and circulate aqua of concentration which decreases from the point of strong aqua intake to said drum to the point of weak aqua discharge from said drum; a bubble tower including bubble plates, said tower being interposed between the vapor offtake of the generator and the condenser inlet and serving both to rectify and cool the ammonia vapor passing therethrough; means for supplying strong aqua to said tower at an intermediate point therein to flood the lower plates thereof; means for supplying strong aqua from the absorber to the surge drum; means for supplying strong aqua to each of said units to cause ejector circulation of the liquid therein; and means for supplying substantially anhydrous ammonia liquid to said

tower adjacent the top thereof to flood the plates above said strong aqua intake but at a rate insufficient to cause discharge of ammonia liquid from the bottom of the tower.

6. In a refrigeration system of the absorption type, comprising a generator, a condenser, an absorber, an evaporator, and means for conveying refrigerant from the generator to the evaporator; a bubble tower interposed between the generator and condenser and having a plurality of bubble plates, said tower serving to rectify and to cool the ammonia vapors passing upwardly therethrough; means for supplying substantially anhydrous ammonia liquid from said condenser to said bubble tower adjacent the top thereof to flood certain of the plates with liquid ammonia; means for returning one portion of the strong aqua from the absorber to the generator; and means for supplying another portion of strong aqua to an intermediate point in said bubble tower.

7. In a refrigeration system of the absorption type, comprising a condenser, an absorber, an evaporator, and a generator for supplying gaseous refrigerant to said condenser, said generator having ejector liquid circulating means; a bubble tower interposed between the generator and condenser and having a plurality of bubble plates, said tower serving both to rectify and to cool substantially to condensing temperature the ammonia vapors therein; means for supplying substantially anhydrous ammonia liquid from said condenser to said bubble tower adjacent the top thereof to flood certain of the plates with liquid ammonia; means for returning one portion of the strong aqua from the absorber to the generator through said ejector liquid circulating means; and means for supplying another portion of strong aqua to an intermediate point in said tower.

8. In a refrigeration system of the absorption type, comprising a generator, a condenser, an absorber, an evaporator, and means for conveying refrigerant from the generator to the evaporator; a bubble tower interposed between the generator and condenser and having a plurality of bubble plates, said tower serving to rectify and to cool the ammonia vapors passing upwardly therethrough; means for supplying substantially anhydrous ammonia liquid from said condenser to said bubble tower adjacent the top thereof to flood certain of the plates with liquid ammonia; means for returning one portion of the strong aqua from the absorber to the generator; means for returning another portion of strong aqua to an intermediate point in said bubble tower; means for controlling the supply of said anhydrous ammonia to said tower in accordance with the temperature differential between the liquid ammonia flowing from the condenser and the ammonia vapor leaving the tower; and means for maintaining a predetermined ratio between the weak aqua and the ammonia vapor flowing to the absorber.

9. In a refrigeration system of the absorption type, comprising a generator, a condenser, an absorber, an evaporator, and means for conveying refrigerant from the generator to the evaporator; a bubble tower interposed between the generator and condenser and having a plurality of bubble plates, said tower serving to rectify and to cool the ammonia vapors passing upwardly therethrough; means for supplying substantially anhydrous ammonia liquid from said condenser to said bubble tower adjacent the top thereof to flood certain of the plates with liquid ammonia;

means for returning one portion of the strong aqua from the absorber to the generator; means for returning another portion of strong aqua to an intermediate point in said bubble tower; automatic means responsive to the temperature differential between the liquid ammonia in the condenser and the ammonia vapor in the top of the tower for controlling the supply of anhydrous ammonia to the tower; and automatic means responsive to the rate of flow of both the weak aqua and the ammonia vapor to the absorber for controlling the rate of flow of said weak aqua.

10. In a refrigeration system of the absorption type comprising a generator, a condenser, an evaporator, means for delivering substantially anhydrous ammonia vapor from said generator to said condenser, and means for causing the ammonia to be delivered in liquid form to said evaporator; an absorber made up of a plurality of serially related spray type gas absorbing units; means for cooling said units; means for delivering ammonia gas from said evaporator to each of said units individually; means for delivering weak aqua from the generator to the first of said units and spraying it over a wide area in said unit and in direct absorbing relation to the entering ammonia gas; means for delivering the aqua from the first unit to another of said units and spraying it in absorbing relation to the ammonia gas therein; means for collecting the strong aqua from the last of said units and supplying at least a portion of it to said generator; automatic means for controlling the treatment of the anhydrous ammonia vapor leaving the generator in accordance with the temperature differential between said vapor and the liquid ammonia leaving the condenser; and automatic means responsive to the rate of flow of both the weak aqua and the ammonia vapor to the absorber for controlling the rate of flow of said weak aqua to said first unit.

11. In a refrigeration system of the absorption type comprising a generator, a condenser, an evaporator; means for delivering substantially anhydrous ammonia vapor from said generator to said condenser, and means for causing said vapor to be delivered in liquid form to said evaporator; an absorber comprising a plurality

5 of surface heat exchange units; connections for delivering anhydrous ammonia vapor from the evaporator to said units in parallel; connections of low flow resistance for passing weak aqua derived from the generator, serially through said units and for flowing it over the heat exchange surface in each of said units in direct absorbing relation with the ammonia vapor, said vapor connections to the units being so constructed and arranged 10 that the vapor entering the units is free of resistance opposed by aqua in the said units; connections for supplying cooling medium for each of said units, the arrangement being such that the units are maintained at successively lower 15 temperatures in the direction of flow of the aqua; and means for delivering strong aqua from the last unit to said generator.

12. The combination defined in claim 11 in which a single cooling medium and the aqua 20 both pass serially through the units in counter flow relation.

13. In a refrigeration system of the absorption type comprising a generator, a bubble tower, a condenser, an evaporator; means for delivering 25 substantially anhydrous ammonia vapor from said generator to said condenser by way of said bubble tower, and means for causing said vapor to be delivered in liquid form to said evaporator; an absorber comprising a plurality of surface heat exchange units; connections for delivering anhydrous ammonia vapor from the evaporator to said units in parallel; connections of low flow resistance for passing weak aqua derived from the generator, serially through said units and for 30 flowing it over the heat exchange surface in each of said units in direct absorbing relation with the ammonia vapor, said vapor connections to the units being so constructed and arranged that the vapor entering the units is free of resistance 35 opposed by aqua in the said units; connections for supplying cooling medium for each of said units, the arrangement being such that the units are maintained at successively lower temperatures in the direction of flow of the aqua; and means for delivering strong aqua from the last 40 unit of said absorber to said generator, at least a part thereof passing through said bubble tower.

WALTER R. McGINNIS.
